UNITED STATES PATENT OFFICE.

JAMES F. MARSHALL, OF WHITINSVILLE, MASSACHUSETTS, ASSIGNEE, BY MESNE ASSIGNMENTS, TO DRAPER CORPORATION, OF HOPEDALE, MASSACHUSETTS, A CORPORATION OF MAINE.

WEFT-PARTER DEVICE FOR WEFT-REPLENISHING LOOMS.

1,291,058.

Specification of Letters Patent. Patented Jan. 14, 1919.

Application filed January 3, 1916. Serial No. 69,707.

To all whom it may concern:

Be it known that I, JAMES F. MARSHALL, a citizen of the United States, residing at Whitinsville, in the county of Worcester, State of Massachusetts, have invented a certain new and useful Improvement in Weft-Parting Devices for Weft-Replenishing Looms, of which the following is a specification, reference being had therein to the accompanying drawings.

The invention is designed for use in those looms, for instance feeler looms, in which prior to complete exhaustion of the supply of weft upon the weft-carrier contained in the shuttle on the lay of a loom such weft-carrier is replaced automatically by a loaded or filled reserve weft-carrier. It has relation to the weft-parting devices which are employed in such looms to part the length of old weft that extends from the selvage of the cloth through the delivery-eye of the shuttle to the old weft-carrier, so that as the said weft-carrier falls it may clear from the shuttle the portion of the said old weft which remains connected with the old weft-carrier.

The invention, more particularly, is an improvement in weft-parting devices of a type in which the parting-members are arranged and caused to enter the shuttle and to sever or part therein the old weft at a point between the old weft-carrier and the outside of the shuttle. It comprises, more especially, novel and improved means of producing the parting action of the parting-members. Briefly stated, the invention resides in the combination with a movably-mounted weft-parting device of the said type, of a cam or actuator that is mounted independently of the lay upon a convenient support in convenient proximity to the lay, and arranged and adapted to produce the parting action of the weft-parting members within an opening in the shuttle. Also, in a construction providing for certain adjustments. Also, in certain features of construction whereby during the closing of the parting-members they are caused to bear closely against each other so as to insure a proper parting action.

An illustrative embodiment of the invention is shown in the drawings, in which latter,

Figure 1 is a side elevation of certain por-

tions of a loom with the said embodiment applied thereto.

Fig. 2 is a front elevation of certain of the parts that are shown in Fig. 1.

The weft-parting devices with which the features of the present invention are associated in the drawings are, in general, not of my invention. The said devices, therefore, will be described but briefly, except as may be required for a proper explanation of my own invention. They are shown located at the outer side of the disk 20 forming a part of the rotary magazine or feeder of the replenishing mechanism and serving in practice to support the tips of a series of weft-carriers applied to the said magazine or feeder, and between the said disk 20 and the flaring disk 21 and weft-end attaching hub 22, Fig. 2. The parts 21 and 22, and a portion of the disk 20, are omitted from Fig. 1 in order that the weft-parting details may appear more clearly in the latter. The parting members 2, 3, of the said devices normally occupy a position above that assumed by the shuttle 1 when the lay 9 is at front center with the shuttle in the shuttle-box at the replenishing side of the loom. They are constructed, arranged, and operated to cause their lower portions to enter by a movement downward, in an open or spread-apart condition as in Fig. 1, into an opening, cavity, or chamber in the shuttle adjacent the delivery-eye of the shuttle, and in thus entering to pass down at opposite sides of the weft on its way from the weft-carrier that is contained in the shuttle to the said delivery eye, and to then close upon the said weft and part or sever the same, and to then withdraw from the shuttle. In the present case, the said members are shaped as blades and adapted to be opened and closed like a pair of shears. One of them is fixedly attached to their common support or carrier 4 and the other is pivoted thereto at 5. Member 3 is held normally in open position relative to member 2 by means of a contracting spiral spring 18 having one end thereof engaged with tail 3^a of member 3 and the other end thereof engaged with support or carrier 4. Their lower ends are caused to enter the shuttle between the weft-carrier therein and the delivery-eye in time to part the old weft substantially as the old weft-carrier is ejected, preferably just a trifle ahead there-

100
105

of, so that the old weft having been parted between the old weft-carrier and the delivery-eye of the shuttle, the falling weft-carrier may take with it the free end of the old weft. The entry of the weft-parter into the shuttle cavity should take place, in other words, substantially at the same time, but usually with a slight lead in time, that the transferrer transfers a reserve weft-carrier 10 into the shuttle and ejects from the latter the old weft-carrier previously contained therein. In the construction shown in the drawings the transferrer and its movements up and down again are utilized for the support 15 and actuation of the weft-parter. Thus, the support or carrier 4 is shown provided with an arm or extension which is made fast by a bolt 4^a and a suitable nut and washers to an arm 6, projecting from a hub 6^a, mounted 20 upon an outwardly projecting sleeve-like extension of the hub 7^a of the transferrer 7^b. The hub 6^a is made fast to the said sleeve-like extension of the transferrer hub by means of a clamping screw 6^b, so that when 25 the transferrer is rocked downward through the engagement of the bunter 8 carried by the lay 9 with the dog or latch 10 hung to the depending transferrer arm at 11 the spent weft-parter will descend in unison 30 with the transferrer. The weft-parter will also be raised by and with the transferrer when the latter is swung upward again through the action of the operating spring 12, surrounding the sleeve-like extension of 35 the transferrer-hub and having one end thereof engaged with the collar 12^a made fast by a clamping screw 12^b upon the said extension and the other end thereof engaged with the arm 13^a carrying the usual tip-sup- 40 port and projecting inwardly and rearwardly from the hub 13 mounted upon the outer extremity of the transferrer-supporting stud 14 and made fast upon the said stud by means of a clamping screw 15. 45 Referring now to my improved means for operating the movable member 3 of the weft-parter in proper time-relations with respect to its entrance into the shuttle-opening, and to the ejection of the old weft-carrier so as to effect the parting of the old weft prior to the descent of the said weft-carrier: I provide an abutment or cam 16 relative to which the weft-parter members are moved in their descent and subsequent rise, and 50 through the action of which the movable member is closed relative to the other member. The said cam 16 has an acting face which by its action, during the descent of the weft-parter, against a roll 17 mounted 55 on a stud 17^a projecting from the tail 8^a of movable parting-member 3, causes the movable member to turn around its pivot 5 and thereby close relative to the opposing member 2. Spring 18 opens the movable 60 member 3 away from the fixed member 2 as 65

the weft-parter rises again. The cam 16 is supported upon the outer end of the transferrer-supporting stud 14 through being provided with an arm which is made fast by a bolt 16^a and a nut and washers to an arm 70 16^b having a hub 16^c that is fitted upon the said stud 14 and made fast thereto by a clamping screw 16^d, Fig. 1. Through mounting the arms 16^b by means of a hub and clamping screw upon the stud 14, and 75 through mounting the arm 6 by means of its hub and the clamping screw 6^b upon the sleeve-like extension of the transferrer hub, convenient provision is made for adjustment to cause the weft parter members to descend to the proper extent within the shuttle-opening, and to provide for proper clearance between the stationary up-raised weft-parter members 2 and 3 and the 80 top of the shuttle and that of the shuttle-box front as the lay swings forward and rearward, as well as for adjustment of the timing of the closing action of the weft-parter members. To provide for proper clearance between the working ends of the 85 weft-parter members 2 and 3 and the front and rear walls of the shuttle-throat, the hole that is provided in the arm of weft-parter support or carrier 4 for the stem of the bolt 4^a is made as a slot 4^b extending lengthwise 90 of the arm, thus providing for shifting the said support or carrier in the direction from front to rear. To enable the proper extent of closing action to be secured the cam 16 likewise is made adjustable through its arm 100 being slotted lengthwise at 16^c for the stem of the bolt 16^a. This enables the said cam to be set farther rearward or forward as may be required.

Referring now to the features of construction whereby during the closing of the parting-members they are caused to bear closely against each other so as to insure a proper parting action:—For the purpose of causing the parting-members to bear closely against each other during their closing, so as to insure a proper parting action, I make provision for cramping the working portion or blade of the parter-member 3 toward and against the working portion or blade of the 110 member 2 as the closing action takes place. To such end, the roll 17 is mounted upon the supporting stud 17^a at a point located at some distance laterally from the member 2, at the side of the latter opposite that at which 115 the member 3 is located. Hence, as roll 17 encounters and travels over the acting portion of the cam 16, there is a tendency to cant or tip the member 3 transversely relative to the member 2 upon the pivotal mounting 120 5, so as to press the member 3 sidewise against the adjacent side of the member 2, thereby insuring an efficient shearing cut.

As a feature of the general construction to which the invention hereinabove described 130

is applied the extent of the opening movement of the member 3 away from the member 2 is determined by means of a stop-screw 19 applied to the support or carrier 4 and 5 having one end of the same arranged in position to be encountered by the back of the parter-member 3 as it opens away from the member 2. By means of the said stop-screw the proper clearance between the free extremity of member 3 and the rear wall of 10 the shuttle-throat as the weft-parter blades or members descend into the said throat is provided for. The drawings show provisions whereby the front blade 2 may be adjusted with reference to the front wall of 15 the shuttle-throat, the said blade being hung by its upper end upon the pivot 5, and having a forward extension that is slotted at 2^a for the stem of the bolt or screw 2^c which 20 fixes it in position upon the carrier or support 4. This slot enables the member 2 to be set forward or rearward as required.

As is usual in practice, the outer portion or starting-end of the weft carried by a 25 weft-carrier mounted in the magazine or feeder is extended in an oblique direction outward from the weft-carrier over the edges of the disks 20 and 21 to the attaching hub 22. In the case of the weft parter devices 30 to which my invention is shown applied, when the weft-parter members occupy their normal upraised and retracted position shown in Fig. 1, the lower portion of the member or blade 3 stands in such position 35 that the starting-end extending from the leading weft-carrier in the magazine or feeder across the edges of the disks 20, 21, to the attaching hub 22, such weft-carrier being in contact with the usual fixed end- 40 stop 23, lies against the back of the said member 3, which is recurved slightly as shown in Fig. 1. Thereby the said starting-end is detained and prevented from entering between the weft-parter members, so as 45 to prevent it from being acted upon and parted or severed by the weft-parter when the latter is called into action. As the weft-parter and transferrer together with the said weft-carrier descend in unison for the pur- 50 poses of the transferring and welt-parting operations, the said starting end of weft remains at the back of the member 3 while the parting of the spent weft connected with the weft-carrier previously contained in the 55 shuttle is effected. The rise of the trans- ferrer and weft-parter to their normal ele- vated position withdraws the weft parter member 3 from the said starting end, so that the latter is left free between the attaching hub 22 and the weft-carrier just inserted 60 into the shuttle.

The point at which the old weft is severed within the shuttle may vary in practice more or less with relation to the delivery- 65 eye. The said point may be located in the

eye itself or at a point a short distance from the eye proper. In either case so small a portion of weft will extend from the outside of the shuttle into the said eye or into and through such eye that such portion will 70 escape or be discharged readily from the shuttle-eye, without danger of being detained therein and carried into the shed by the next flight of the shuttle across to the other side of the loom.

In practice, means usually will be provided for insuring the clearing of the free end of the old weft from the shuttle-eye, such for instance as the swinging arm 24, Fig. 2, which in practice at the proper time 80 is actuated so as to swing or rotate rearwardly into position to engage with the portion of old weft extending outward from the selvage of the cloth being woven to the shuttle, and then swing or rotate forwardly 85 so as to withdraw the outer extremity of such portion of weft from the delivery-eye of the shuttle. The arm 24 is shown as toothed or notched, to enable it to engage with the old weft with more certainty and 90 prevent the latter from slipping downward along the said arm as it swings or rotates forwardly. This action of the arm 24 may be and ordinarily will be utilized to draw the said weft into the range of action of a 95 selvage weft-parter in connection with the adjacent temple 33.

The actuation of the transferrer and weft-parting device is controlled in practice by shuttle-feeler devices. The drawings show 100 one arrangement of such devices, which, however, form no part of the present invention. They comprise a shuttle-feeler 51 that is pivoted at 52 upon the inner side of the upper portion of the fixed stand 53 105 of the magazine or feeder. The said shuttle-feeler is actuated through connections with the breast-beam rockshaft 34 and has the usual function of detecting failure of the shuttle to enter fully into the shuttle- 110 box and of preventing the actuation of the transferrer in case of such failure. In addition it performs the duty, as will be apparent, of preventing the described weft-parter device from being actuated in case 115 the shuttle is out of its proper position. Thereby injury to the weft-parter blades or members, or other parts of the weft-parter device, as a result of the ends of the said blades or members being caused to 120 strike upon some portion of the shuttle, is prevented. In the present instance, the upper arm of the shuttle-feeler is connected by means of a link 54 to the upper arm of a lever 55 which is pivoted at 56 upon an 125 arm 57 fixed upon the breast-beam rock- shaft 34 and extending upward therefrom. By means of a contracting spiral spring 58 engaged with the lower arm 55^a of the lever 55 and also with a stud 59 carried by 130

a branch 57^a of the arm 57, the said lower arm 55^a is held normally in contact with an adjustable stop constituted by a set-screw 60 carried by the arm 57. Arm 55^a is slotted at 55^b and receives in its slot a projection or stud 10^a from the holder of the dog or latch 10 of the transerrer. Thereby the position of the said dog or latch is controlled. Through the connections described, the shuttle-feeler and the dog or latch 10 are combined operatively with the breast-beam rockshaft 34, so that when the said rockshaft is rocked for the purpose of calling a transfer, the acting 15 end of the shuttle-feeler is moved rearward into feeling position, and simultaneously therewith the dog or latch 10 is raised into the path of the engaging portion of the bunter 8 carried by the lay, so that as the 20 lay comes forward the bunter may engage the dog or latch and actuate the transerrer and spent weft-parter. The tension of spring 58 is sufficient to hold lever 55 normally in engagement with stop 60, and 25 to cause such lever to move in unison with the arm 57 just as though it were one piece therewith, to thereby call the shuttle-feeler and the dog or latch into operation, provided no encounter between the shuttle- 30 feeler and the shuttle takes place. In case of such encounter as the lay moves forward, the shuttle-feeler will be forced forward and through the connection of the shuttle-feeler with the lever 55 the latter will be 35 turned on its pivotal connection 56 with the arm 57 so as to swing the dog or latch 10 down out of the path of the engaging portion of the bunter 8. Thereby the actuation of the transerrer and of the weft- 40 parter will be prevented, thus safeguarding as usual against the bad results following from the attempt to effect the transfer with the shuttle in improper position, and in addition avoiding injury to the weft-parter.

45 I claim as my invention:

1. In a loom, the combination with a movably-mounted weft-parter device that is operated to cause the same to enter an opening in the shuttle, of a cam mounted independently of the lay and by which the said weft-parter device is caused to part the old weft within the said opening and a support adjacent the lay for the said cam.

55 2. In a loom, the combination with a movably mounted weft-parter device that is operated to cause the same to enter an opening in the shuttle, of a fixed cam that is mounted upon the loom-frame and by which the said weft-parter device is caused to part the old weft within the said opening.

60 3. In a weft-replenishing loom, the combination with a transerrer, and a weft-parter device that is connected with said transerrer and moved in unison therewith to 65 cause it to enter an opening in the shuttle, of

a fixed cam that is mounted upon the loom-frame and by which the said weft-parter device is caused to part the old weft within the said opening.

4. In a loom, the combination with a weft-parter device comprising relatively movable members adapted to coöperate in parting the old weft, and operated to cause the said members to enter an opening in the shuttle, of a cam mounted independently of the lay 75 and by which relative movement of the said members within the said opening is produced and the old weft thereby parted and a support adjacent the lay for the said cam.

5. In a weft-replenishing loom, the combination with a transerrer, and a weft-parter device that is actuated thereby, comprising relatively movable members that are caused to enter an opening in the shuttle through the actuation by the transerrer, of 80 a cam mounted independently of the lay and by which relative movement of the said members within the said opening is produced and the old weft thereby parted and a support adjacent the lay for the said cam. 90

6. In a loom, the combination with a weft-parter device comprising relatively movable members adapted to coöperate in parting the old weft, and operated to cause such members to enter an opening in the 95 shuttle, of a spring by which said members normally are held open, a cam mounted independently of the lay and by which the said members are closed within the said opening to part the old weft therein and a 100 support adjacent the lay for the said cam.

7. In a loom, the combination with a movably-mounted weft-parter device comprising coöoperating relatively movable blades and operated to cause such blades to enter an 105 opening in the shuttle to engage with the old weft therein, of a cam engaging a laterally off-set follower with which one of said blades is provided, whereby relative movement of the blades while within the opening 110 is produced and such blade is caused to bear closely against the opposite member during the parting action.

8. In a loom, the combination with a weft-parter device comprising relatively 115 movable blades or members and a support or carrier therefor normally occupying a retracted position with said blades or members withdrawn from the shuttle, movable to cause them to enter an opening in the shuttle 120 to engage and act upon the weft therein, and adjustable to provide for clearance of the blades or members within such opening, of a cam that is mounted independently of the lay, and by which relative movement of said 125 blades or members is produced to part the old weft within the opening, and a support adjacent the lay for the said cam, said cam adjustable in accord with the adjustment of the support or carrier. 130

9. In a loom, the combination with a weft-parter device comprising relatively movable parting members and a swinging arm constituting a support or carrier therefor, normally occupying a retracted position away from the shuttle and movable to cause said members to enter an opening in the shuttle and engage the weft therein, said members adjustable lengthwise of the arm to provide for proper entry and clearance within the opening, of a cam mounted independently of the lay and by which relative movement within the opening of said members is produced to part the old weft, and a support adjacent the lay for the said cam, said cam adjustable in accord with the adjustment of the support or carrier.
10. In a weft-replenishing loom, the combination with the transferrer, and a weft-parter device comprising an arm connected with the transferrer and relatively movable parting members carried by the said arm, movement of said arm with the transferrer at the time of a transfer causing said members to enter an opening in the shuttle and engage the weft therein, said parting members adjustable lengthwise of the arm to provide for proper entry and clearance within the opening, of a cam mounted independently of the lay and by which relative move-

ment of said members within the opening to part the old weft is produced, and a support adjacent the lay for the said cam, said cam adjustable in accord with the adjustment of the support or carrier.

35

11. In a weft-replenishing loom, the combination with the transferrer and its supporting-stud, of a weft-parter device comprising relatively movable blades or members and a support or carrier therefor connected with the transferrer upon said supporting-stud and normally occupying an elevated position with said blades or members withdrawn from the shuttle, movement of the support or carrier at time of a transfer causing said blades or members to enter an opening in the shuttle, and a cam that is mounted upon a support in connection with said supporting-stud and by which relative movement of said blades or members is produced to part the old weft within the opening, said support or carrier and cam respectively adjustable angularly around the said supporting-stud.

In testimony whereof I affix my signature in presence of two witnesses.
